UNITED STATES PATENT OFFICE.

BASIL BREWER, OF CLEVELAND, OHIO.

PAPER-MEASURING ATTACHMENT FOR PRINTING-PRESSES.

1,391,042.

Specification of Letters Patent. Patented Sept. 20, 1921.

Application filed March 6, 1920. Serial No. 363,679.

To all whom it may concern:

Be it known that I, BASIL BREWER, a citizen of the United States, residing at Cleveland, in the county of Cuyahoga and State 5 of Ohio, have invented a certain new and useful Improvement in Paper-Measuring Attachments for Printing-Presses, of which the following is a full, clear, and exact description.

10 The present invention relates to printing presses, particularly large presses, such as are employed for printing newspapers, and to which paper stock is applied in the form of large rolls.

15 In ordering from a paper manufacturer, rolls of paper for use on presses for printing newspapers and the like, a certain thickness of paper is always understood or stipulated so that since the weight of the roll is 20 known, the length of paper on the roll, and hence the number of papers that can ordinarily be printed from it can be determined providing paper of the desired or designated thickness is furnished. It is often the case, 25 however, that the paper manufacturer does not furnish paper of the proper thickness, the paper being sometimes thicker than desired, in which event the length of paper on the roll is less than it should be, and less 30 than the desired number of printed newspapers is obtainable from a roll.

The principal object of the present invention is to provide a measuring attachment applied to the press in such a way that the 35 amount of paper in length units can be accurately measured.

Further the invention aims to apply a measuring device to a roll of the press over which the paper passes in passing from the 40 roll of paper to the printing rolls, the point of application of the measuring device, or the manner in which it is applied to the machine being such that inaccuracies due to slippage of the paper relatively to the rolls 45 or devices over which the paper passes, or due to irregularities in the speed of operation of the press, or due to breakage of the paper at some point distant from the measuring device, are avoided.

50 The invention may be briefly summarized as consisting in certain novel combinations and arrangements of parts which will be described in the specification and set forth in the appended claims.

55 In the accompanying sheet of drawings wherein I have shown an embodiment of my

invention which operates with high efficiency, Figure 1 shows one printing unit of a standard newspaper press; Fig. 2 is an enlarged view, partly in horizontal section 60 and partly in plan view showing the measuring attachment applied to a spring roller which is adjacent the roll of paper; Fig. 3 is an enlarged side view looking toward the right of Fig. 2, showing the mounting of the 65 spring roller in question with the measuring device removed; and Fig. 4 is a similar view with the measuring device in place.

A printing press for printing newspapers usually consists of a number of printing 70 units, each usually having provision for supporting two rolls of paper, also having two sets of printing rolls, inking devices, rolls or rollers over which the paper passes as it passes from the roll or rolls of paper through 75 the machine, and folding and cutting devices, and numerous other instrumentalities which are immaterial to the present invention and need not be here referred to. In Fig. 1 I have shown conventionally the 80 major portion of one printing unit of a standard press. In this figure 10 and 11 represent two rolls of paper supported in proper position with respect to the parts of the printing unit referred to, so that the 85 paper can be fed first from one roll, and then from the second roll, if the paper on the two rolls is of full width, or if the rolls are of a length such that single sheets are to be 90 printed, the paper may be run from both rolls at the same time, one roll then being displaced axially with respect to the other.

From the roll or rolls the paper passes around a roll 13, to which my improved measuring device is applied for reasons to 95 be subsequently referred to, then around other rolls 14 and 15, then through the printing rolls 16, to which ink is applied by inking means consisting of a plurality of rolls designated generally by the reference character 17. Then the paper passes around other suitably positioned rolls 18, 19 and 20 to the other portions of the press not shown.

The roll 13 which is next to the paper rolls may be termed a spring roll, as its shaft 21 is mounted in bearing blocks 22 slidable in guideways 23 of brackets 24 secured to the frame-work 25 of the press, the movement of the roll toward the paper rolls being resisted by coil springs 26, which permit a to 110 and fro movement of the roll 13 as the tension in the paper varies. All the other rolls

of the press are generally mounted in normally fixed bearings.

When the rolls are received from the paper manufacturer it is generally the case that 5 they are not cylindrical in shape, and in many instances are not even approximately so, but due to rough usage in transit they are more or less oval, some portions being compressed, and others bulged outward. In consequence 10 when a roll of this shape is placed in the press and the paper is fed from it, it becomes necessary for smooth operation of the press, that the roll over which the paper passes as it leaves the paper roll be yieldingly 15 mounted so that it may act as an equalizer, either moving bodily to and fro in the brackets which support it, or with an oscillatory movement so that the non-uniform feeding of the paper from the roll is compensated 20 for, and an even tension maintained in the paper passing through the machine.

It is to one end of this roll of each printing unit of the press that I prefer to provide my improved measuring device which 25 is indicated at 27 in the drawings. The details of the measuring device are immaterial to my invention, and it will be sufficient to state that it is mounted on the sliding bearing block at one end of the shaft 21 which 30 carries the roll 13, so as to move back and forth with the latter, and it is actuated by an extension of the shaft 21. The measuring 35 device may be in any suitable units, but preferably in length units of any denomination, such as feet or yards.

By applying the measuring device to the spring supported roll 13, a far more accurate measurement is obtainable than is possible 40 with the measuring device applied to any other rotary part of the press. It is apparent that slippage between the paper and roll upon which the measuring device is applied, would prevent accurate measurement of the paper passing over the periphery of the roll, but since the roll 13 is spring mounted and adapts itself to uneven feed 45 of the paper, the slippage between this roll and the paper is negligible. Furthermore, 50 this roll has a large portion of its periphery engaged by the paper as it passes around it, and is usually corrugated.

A further advantage, aside from that mentioned, and due to the fact that the measuring device is applied to the roll next to the roll of paper, is that the accuracy of the measurement is not affected by breakage of the paper which frequently occurs at some point near or beyond the printing rolls. 55 When the breakage occurs, the operator usually is required to destroy a considerable length of the paper which is bodily pulled out of the machine, but the length of this destroyed paper is recorded on the measuring device, which would not be the case if 60

the measuring device were at a distance from the paper roll or rolls and the destroyed section were removed between the paper rolls and the measuring device.

I am aware of the fact that measuring devices have been applied to certain types of machines, particularly for measuring cloth, but never to my knowledge has any one successfully applied a length measuring device to a printing press to measure the length of 70 paper passing from the roll. Nor to my knowledge has any one conceived the idea of applying such a measuring device either to any rotary part constituting a fixed or standard part of the press or to any special 75 roll or roller applied for the purpose of accommodating the measuring device. As I believe I am the first to obtain the measurement of the length of the paper fed from the roll of a press by the practical application 80 of a measuring device in such a way that accurate results are obtained, I regard it as immaterial to my invention in its broad aspects, to what rotary part of the press the device is applied, though I regard it as of 85 extreme importance that it be applied to the spring roll adjacent the rolls of paper, and my invention in its more specific aspects resides in such application.

Having described my invention, I claim: 90

1. The combination with a printing press adapted to accommodate paper in roll form, and having a plurality of rolls around which the paper passes as it travels through the press, including a yieldable roll which may 95 yield under varying tension of the paper, of a measuring attachment operatively connected to such roll.

2. The combination with a printing press adapted to accommodate paper in roll form, 100 and provided with a plurality of rolls about which the paper passes when traveling through the press, including a yieldingly mounted spring roller which may yield as the feed of paper varies, of a measuring device operatively connected to the shaft of such spring roller and adapted to measure 105 in appropriate units the length of paper fed from the roll.

3. The combination with a printing press adapted to accommodate paper in roll form, 110 and having a plurality of rolls about which the paper passes in traveling through the press, one of said rolls located adjacent the point of support of the paper roll having 115 spring resisted movable bearings such that the roll may yield under non-uniform feed of paper, of a measuring device operatively connected to said roll for the purpose of measuring in appropriate units the length 120 of paper fed through the machine.

In testimony whereof, I hereunto affix my signature.

BASIL BREWER.
